UNITED STATES PATENT OFFICE.

JESSE DEE TUCKER AND EMMITT M. TUCKER, OF NORTH SACRAMENTO, CALIFORNIA.

CARBURETER.

1,329,686.

Specification of Letters Patent.

Patented Feb. 3, 1920.

Application filed April 13, 1918. Serial No. 228,511.

To all whom it may concern:

Be it known that we, JESSE D. TUCKER and EMMITT M. TUCKER, both citizens of the United States of America, residing at North 5 Sacramento, county of Sacramento, State of California, have invented certain new and useful Improvements in Carbureters; and we do declare the following to be a clear, full, and exact description of the same, reference being had to the accompanying drawings, and to the characters of reference marked thereon, which form a part of this 10 application.

This invention relates to improvements in 15 carbureters for use in connection with all types of internal combustion engines. The prime object of the invention is to provide a carbureter which will properly proportion the explosive mixture so that the quantity 20 of oxygen taken into the cylinders of the engine will at all times be sufficient to burn a maximum amount of the hydrogen and carbon present in the fuel.

A further object of the invention is to 25 provide a carbureter whereby a full charge of explosive mixture will be taken into each cylinder of the engine with each suction stroke of the piston therein irrespective of the speed at which it may be traveling.

30 With the above objects in view, we aim to admit through the carbureter all the air demanded by the engine and then admit and control the fuel supply in direct relation to the air. In other words, a full air supply is 35 given first consideration and the fuel is admitted only in such proportion thereto as will cause the resulting mixture when fired to effect the complete combustion of the gases.

40 We especially aim to use low grade fuels such as distillate, kerosene or the like with better results than are now obtained with the use of gasoline or other highly volatile oils.

45 A still further object of the invention is to produce a simple and inexpensive device and yet one which will be exceedingly effective for the purposes for which it is designed.

50 These objects, we accomplish by means of such structure and relative arrangement of the parts as will appear by a perusal of the following specification and claims.

On the drawings, similar characters of 55 reference indicate corresponding parts in the several views.

Figure 1 is a vertical section through the entire carbureter.

Fig. 2 is a detached view of a priming valve in section. 60

Fig. 3 is a detached view of a fourway valve in section.

Fig. 4 is a detached view of an air inlet diaphragm.

Referring now more particularly to the characters of reference on the drawings, the numeral 1 designates the float chamber in which is located a valve controlling float 2 of desired type. Arranged adjacent the float chamber 1 is the primary carbureting 65 chamber 3 into which projects the fuel jet 4. The lower end of this jet 4 is arranged to communicate with a fourway valve 5 having a control lever 6. A port 7 communicates from the chamber 1 to the fourway 70 valve 5 whereby it may be placed in communication with the jet 4. A port 8 leads from any suitable source of fuel supply such as gasoline or other highly volatile fuel 75 which may be placed in connection with the jet 4 for the purpose of starting the motor to which the carbureter may be connected. A drain port 9 is likewise arranged to be placed in connection with either of the ports 80 7 or 8 (for any purpose.)

A sleeve 10 surrounds the tapered end of the jet 4 and terminates at its upper end in a dished flange 11. This sleeve is provided with air openings 12. A centrally orificed dished washer 13 is interposed between the 90 side walls of the carbureting chamber 3 and the flange 11 and overlaps the edges of the said flange 11 a small distance, as at 11^a. The washer is held normally in contact with the flange by means of a spring 14 interposed between the bottom periphery of the upper carbureting chamber 15 and the said washer 13. 95

The numeral 16 designates the main air inlet of the carbureter which is relatively 100 large and communicates with the main carbureting chamber 3 below the flange 11 and the washer 13. A needle valve 17 controls the opening of the jet 4 and is provided with a stem 18 which projects vertically 105 through the chambers 3 and 15 and terminates in a disk 19 movable within a guide cylinder 20. The disk 19 is preferably screwed onto the end of the stem 18 a desired distance, and then locked in the place 110 thereon by means of a nut 19^a on the stem. This cylinder 20 is mounted for threaded

movement through the top of the chamber 15 where it is provided with a control lever 21 which projects to any desired convenient point such as the dashboard of a motor vehicle. A helical spring 22 is interposed between the top of the cylinder 20 and the disk 19 to normally hold the valve 17 closed.

On the stem 18, at a point between the chambers 3 and 15, is fixed the perforated 10 air inlet diaphragm 23. This diaphragm is screwed onto the stem 18 to a suitable position, and is then held by a lock nut 23^b thereon. Around the stem 18 between the diaphragm 23 and the disk 19 is interposed 15 a sleeve 24. On the lower end of the sleeve 24 is a diaphragm 25 which normally forms a closure for the holes 23^a in the diaphragm 23. On the upper end of the sleeve 24 is a disk 26 which projects into the cylinder 20 20 and is normally disposed at a distance from the disk 19. A helical spring 27 is interposed between the disks 26 and 19. By means of this double spring construction the tension of the air valve spring 27 and the 25 needle valve spring 22 may always be regulated in conjunction with each other.

Thus, if the guide 20 is turned down to compress the spring 22 and press the needle valve 18 tighter in its seat, the spring 27 is 30 not compressed, but its tension relative to the spring 22 is altered, so that the spring 22 becomes stronger than the spring 27. This allows a greater lift of the disk 25 before the needle valve is raised, and consequently a leaner mixture is obtained.

Similarly, if the guide 20 is turned in the reverse direction to release the spring 22, the spring 27 is then relatively stronger than the spring 22, and hence the needle 40 valve 18 is raised almost as soon as the disk 25, thus causing a rich mixture.

By having the sleeve 24 interposed between these pairs of disks, a free area is left in the chamber 15 for the circulation of the 45 mixture.

The numeral 28 designates the outlet from the carburetor for connection with the intake manifold of the engine and in this outlet 28 is the butterfly valve 29 controllable by the lever 30.

The numeral 31 designates a priming valve having a nozzle 32 projecting through the side walls of the chamber 3 and into one of the holes 12 in the sleeve 10. This 55 valve may be opened by any suitable and conveniently located means and admits gasolene or other desired fuel to the carburetor for the purpose of starting. When the engine has been started in this manner, the valve 31 is allowed to close and the valve 60 5 is then moved to connect the port 8 with the jet 4, so that for a short period gasolene will be admitted to the carburetor. Then, after the engine is thoroughly warmed up, 65 the valve 5 is turned to place the port 7 in

communication with the jet 4, whereupon distillate is admitted to the carburetor and thereafter this latter fuel is used.

When the engine is running under normal speed conditions, the cylinder 20 is positioned so that the tension of the spring 27 is greater than the tension of the spring 22 to such a degree that the suction of the air against the disk 25 will lift such disk a very slight distance from the diaphragm 23 before causing the spring 22 to be compressed, which of course raises the disk 19 attached to the valve stem and causes the valve 17 to raise from its seat in the fuel jet 4, thus admitting fuel in direct relation to the amount of air taken into the carburetor. Under these conditions, the air is taken through the opening 16 and holes 12 into the sleeve 10 and thence into contact with the fuel from the jet 4. From there it is drawn through the holes 23^a which cause the fuel to be properly carbureted. It is of course understood that these springs are somewhat sensitive, so that it does not take any great amount of suction or pressure to cause the same to operate. When sudden speed or charge demands are made upon the engine, or whenever the demands of the engine exceed the capacity of the ports 12 the dished washer 13 will be lifted from its seat against the flange 11. A swirl of air is then rapidly taken in and driven downwardly against the other air and fuel and this swirl breaks up the fuel to a very marked degree and thoroughly carburets the same with the necessary inclusion of air required to meet the increased demand of speed, etc., of the engine. No matter what the suction of the engine may be, this additional air inlet occasioned by the latter described construction 100 permits enough air to be taken into the engine. At the same time the spring adjustment construction permits of the regulation of the amount of opening of the fuel jet in direct relation to the amount of air taken into the engine.

When the engine is to be operated in high altitudes or excessive speeds, which require a much greater amount of air than ordinary running conditions, the cylinder 20 is 105 screwed down to increase the tension of the spring 22. This then makes the tension of the spring 22 greater than that of the spring 27 and before the suction of the engine will cause the diaphragm and disks to work 110 against the spring 22, it will first work against the spring 27 and bring the disk 25 clear away from the diaphragm 23 and leave the openings 23^a entirely clear, thus admitting a greater supply of air.

From the foregoing description, it will readily be seen that we have produced such a device as substantially fulfills the objects of the invention as set forth herein.

While this specification sets forth in detail 130

the present and preferred construction of the device, still in practice, such deviations from such detail may be resorted to as do not form a departure from the spirit of the 5 invention, as defined by the appended claims.

Having thus described our invention, what we claim as new and useful and desire to secure by Letters Patent is:—

- 10 1. A carbureter including a primary chamber and a secondary chamber above the same, a fuel jet projecting into the primary chamber, a needle valve in the jet, a stem on the valve projecting upwardly into a 15 guide adjustably mounted in the secondary chamber, a disk on the stem within the guide, a spring between the disk and the upper end of the cylinder to seat the needle valve in the jet, a perforated diaphragm on the stem fitting closely in the throat between the two 20 chambers, and means interposed between the disk and the diaphragm governed by the turning of the guide to regulate the air-fuel ratio.

2. A carbureter including a primary 25 chamber and a secondary chamber above the same, a fuel jet projecting into the primary chamber, a needle valve in the jet, a stem on the valve projecting upwardly into a guide 30 adjustably mounted in the secondary chamber, a disk on the stem within the guide, a spring between the disk and the upper end of the cylinder to seat the needle valve in the jet, a perforated diaphragm on the stem fitting closely in the throat between the two 35 chambers, a spool slideable on the stem above the diaphragm, and a spring interposed between the spool and the disk on the stem, whereby the spool is normally held against the perforated diaphragm to close the same. 40

In testimony whereof we affix our signatures in presence of two witnesses.

JESSE DEE TUCKER.
EMMITT M. TUCKER.
